AIR CONDITIONING SYSTEM

Robert S. Herbst, East Orange, N. J., assignor to General Electric Company, a corporation of New York

Application June 23, 1951, Serial No. 233,231

1 Claim. (Cl. 257—8)

This invention relates to air conditioning systems and particularly to such systems which provide both heating and cooling and are employed for maintaining required temperature conditions throughout the year.

In air conditioning systems, such as warm air systems for heating residences, cooling for summer operation may be provided by connecting a cooling unit to the same room air supply system. It is desirable that either the heating system or the cooling system may be employed without requiring complicated changeover operation. Furthermore, when both heating and cooling are supplied for residential air conditioning, it is desirable that the entire operation of changing over from summer conditioning to winter conditioning be made without requiring special tools or special knowledge of the system. Accordingly, it is an object of this invention to provide in an air conditioning system a simple and effective control for changing from heating to cooling operation including an improved arrangement for changing the air circulating paths. It is another object of this invention to provide an air conditioning unit including a blower and heat transfer surface and an improved automatic air circuit control dependent upon the operation of the unit blower.

Further objects and advantages of the invention will become apparent as the following description proceeds, and the features of novelty which characterize the invention will be pointed out with particularity in the claim annexed to and forming a part of this specification.

In carrying out the objects of this invention an air conditioning system including a warm air heating unit and an air cooling unit is arranged with a common duct for supplying conditioned air to an enclosure. The two units are arranged to be operated alternatively and may be connected either in series or in parallel in the air circuit. In either case, an automatic damper of the check valve type is provided to allow a flow of air through the outlet of the cooling unit whenever the cooling blower is in operation but to prevent such flow whenever the heating unit is in operation. When the two units are arranged to be connected in series, the heating unit outlet supplies air to the inlet of the cooling unit, and the automatic damper is so arranged that the blower and heat transfer surface of the cooling unit are by-passed during heating operation; however, during cooling operation both the heating and cooling blowers may be employed to circulate air in series, thereby providing a boosting effect for summer air conditioning.

For a better understanding of this invention, reference may be had to the accompanying drawings in which Fig. 1 is a diagrammatic illustration of an air conditioning system for summer and winter operation embodying the invention, and Fig. 2 is a diagrammatic illustration of a similar heating and cooling air conditioning system embodying a modified form of the invention.

Referring now to the drawing, the air conditioning system illustrated in Fig. 1 comprises a warm air heating furnace or similar unit 10 and an air cooling unit 11 connected to deliver air through a duct 12 to a room within an enclosure indicated generally by the dot and dash lines. The air is returned from the room for recirculation through the air conditioning system by a duct 13. The heating unit comprises a casing 14 within which is arranged a combustion chamber 15 provided with a fuel burner 16 which may, for example, be a gas burner actuated in accordance with operation of a suitable supply or control unit 17. Combustion air for the burner 16 is supplied through a suitable duct structure (not

2

shown) and the products of combustion rise through the chamber 15 to the top of the casing and are removed through a stack connection 18. A normally closed damper 19 is mounted in the connection 18 and is controlled to be opened whenever the furnace is in operation.

The products of combustion rising from chamber 15 pass around heat transfer tubes 20 through which the air to be heated is circulated by operation of a blower 21 driven by an electric motor 22. The air is admitted to the blower through an inlet duct 23 providing communication between the return air duct 13 and the blower, and the air, after being heated by passage through the tubes 20, is conducted upwardly through a forward manifold passage 24 and passes through a duct 25 to the bottom of the supply duct 12.

The cooling unit 11 comprises a casing 27 divided into a refrigerating machine compartment 28 and a blower compartment 29. Within the blower compartment 29 are arranged a heat transfer surface 30, which may be the evaporator of a refrigerating machine, and a blower 31 driven by an electric motor 32 for circulating air over the heat transfer surface 30. In the compartment 28 is arranged a compression type refrigerating machine driven by an electric motor 33 and including a refrigerant compressor and condenser (not shown), the compressor being driven by the motor 33 through a belt 34 in the usual manner. When the blower 31 is in operation, air is drawn from the return duct 13 through an inlet connection 35 and thence flows to the blower through a passage 36 and a by-pass 37, a pivotally mounted damper 38 being biased to its open position through its connecting rod 39 and a compression spring 40. At least a portion of the air, therefore, thus flows over the heat transfer surface 30 and is delivered to the supply duct 12 to a discharge conduit 41. Under conditions of operation requiring the full cooling capacity of the unit 11, the damper 38 is operated to close the passage 37 so that the entire air stream is circulated over the heat transfer surface.

The selection of the heating or cooling operation is effected by operation of a selector switch and thermostatic control 42. When it is desired to operate the furnace, a manual switch 43 is moved to engage its left-hand contact indicated at 44 and thereby connect a thermostat represented as a bimetallic strip 45 in circuit with the secondary coil of a transformer 46. The transformer is connected across electric supply lines 47. The control 42 is arranged within the space to be conditioned, and when there is a decrease in temperature sufficient to create a demand for heating, the element 45 moves to the right to engage its stationary contact indicated at 48 and thereby connects the electric control of the unit 17 and a solenoid coil 49 in parallel across the secondary of the transformer 46. Energization of the coil 49 lifts an armature 50 and moves the damper 19 to its open position. Energization of the control 17 ignites the burner 16, and as soon as the temperature reaches a predetermined value within the casing 14, as determined by a bimetallic thermostat 52 mounted in the manifold 24, the element moves to the left engaging its stationary contact 53 and connects the motor 22 to the supply lines 47 through a lead 54, a connection 55 and a lead 56. The blower is continued in operation as long as the temperature in the manifold 24 remains above the predetermined value. The heated air is then circulated by the blower 21 through the tubes 20 and out the duct 25 to the supply duct 12. An automatic damper 57 is provided in the duct 25 and is opened by the pressure of the air supplied upon operation of the fan 21. This damper is of the check type and prevents reverse flow through the duct 25, the upper portion of the damper striking a stop 58 when the damper moves in a clockwise direction to its closed position as shown.

When it is desired to operate the air conditioning system for supplying cooling air to the enclosure, the switch 43 of the control 42 is moved to the right to engage its right-hand contact indicated at 60 and thereby connects two bimetallic thermostat strips 61 and 62 to the secondary of the transformer 46. When the temperature in the room to be conditioned reaches a predetermined value constituting a demand for cooling, the strip 61 moves to

the right and engages a stationary contact 63, thereby connecting a coil 64 of a relay 65 across the secondary of the transformer. This energizes the relay, thereby closing it to connect a lead 66 of the cooling unit to the supply lead 56. The motors 32 and 33 are thus connected in parallel across the supply line 47 and operation of the cooling unit is initiated, air being circulated through the casing 27 and a portion of it over the heat transfer surface 30, the conditioned air and by-passed air entering the blower 31 and being discharged through the duct 41 to the supply duct 12. An automatic damper 68 is pivotally mounted in the connection 41 and is opened by the force of air discharged from the blower 31. When the blower 31 is not in operation, the damper 68 returns in a counterclockwise direction until its upper portion engages a stop 69.

Should the temperature within the enclosure continue to rise, the second bimetallic element 62 will move to the right sufficiently to engage a stationary contact 70 and thereby connect a coil 71 across the secondary of the transformer. When the coil 71 is energized in this manner, it attracts an armature 72 attached to the operating rod 39 of the damper 38 and moves the rod to the right in opposition to the spring 40, thereby closing the damper 38. The entire stream of air received from the inlet 35 is then circulated by the blower 31 over the heat transfer surface 30 and the maximum cooling capacity of the unit is realized.

Should the cooling demand be met, the thermostat 62 will open leaving the cooling unit in operation with the by-pass 37 open until the thermostatic element 61 has been satisfied by further reduction in temperature whereupon operation of the unit 11 is suspended, the coil 64 being deenergized and the relay 65 opened.

The dampers 57 and 68 prevent reverse flow of air through their respective conduits 25 and 41. Thus, cooled air is not lost through the warm air conditioner 10, and during the heating season hot air is not lost through the cooling unit 11. This latter feature is particularly desirable in order to prevent heating of the refrigerant in the heat transfer surface 30. These automatic dampers require no attention from the user, it being unnecessary to change damper connections by hand, and furthermore these dampers are simple in their automatic operation and do not require the addition of complicated controls or other devices. The operation of the heating and cooling units is thus coordinated in a manner such that they may be employed effectively without interference because of their connection to a common air circulating system.

The air conditioning system illustrated in Fig. 2 is similar to that shown in Fig. 1 but includes structural changes in the cooling unit and corresponding parts of which have been designated by the same numerals as in Fig. 1 with the addition of the letter *a*. This system differs from that of Fig. 1 in that the heating and cooling units are provided with air ducts such that they may be connected in series in the path of air flow so that the two fans or blowers may be operated together to provide a boosting effect. The cooling unit indicated at 11a differs from the cooling unit 11 of Fig. 1 in that a single automatic damper is incorporated therein which takes the place of both dampers 57 and 68 of Fig. 1. As shown in the drawing, the cooling unit 11a comprises a casing 27a having a blower compartment or chamber 29a intermediate a machinery compartment 28a and a plenum chamber 75 at the top of the unit. The heating unit 10 is provided with a lateral outlet 76 instead of the vertical outlet 25 of Fig. 1 but is otherwise of the same construction in both figures. The outlet 76 is connected directly to the inlet of the unit 11a as indicated at 77 so that the air discharged from the heating unit 10 enters the left end of the plenum chamber 75. In order to control automatically the passages through which air flows in the heating and cooling operations, a damper 78 is pivotally mounted on a transverse axis intermediate an intake opening 79 of the blower chamber 29a and the discharge opening of a blower 31a as indicated at 80. The damper includes an upper portion 81 which, in the position shown, operates the inlet and outlet of the plenum chamber 25 and directs the air downwardly into the chamber 29a. A lower portion 82 of the damper in the position shown

lies within the inlet 79. The damper is biased to its vertical position by gravity action through a laterally offset weight 83. When the blower 31a is not in operation and the blower 21 is started and discharges air from the heating unit 10, the damper 78 is moved by the air pressure and rotates in a clockwise direction to the dotted line position wherein it closes the inlet 79 and the outlet 80 of the blower chamber and prevents the back flow of the air into the blower chamber and thence about the heat transfer surface indicated at 30a. Also in the dotted line position, the weight 83 lies on the right-hand side of the axis of the damper and biases the damper to its dotted line position.

When the damper is in the dotted line position and the blower 31a is placed in operation, the damper is moved by the force of the air discharged by the blower and returned to its vertical position as shown on the drawing. Thus whenever the cooling unit is in operation the blower is in the full line position shown in the drawing.

The control of the system in Fig. 2 is essentially the same as that of Fig. 1 except that a second switch element indicated at 84 is provided on the relay 65a so that when the thermostat 61 calls for cooling, the switch 84 closes a circuit from the line 56 through a lead 85 to the motor 22. Thus during the cooling operation both blowers are energized and air is circulated from the heating unit 10 through the duct 76 and into the blower chamber of the unit 11a through the intake 79 and thence through the blower 31a to the outlet duct indicated at 12a. The two fans, therefore, operate in tandem, the fan 21 providing a booster action for the fan 31a. This general arrangement of the fans for the cooling operation is described and broadly claimed in an application of Samuel J. Levine, Serial No. 119,676, filed October 5, 1949 (now Patent No. 2,498,397), and assigned to the same assignee as the present invention.

It is evident that in the arrangement of Fig. 2 the automatic damper 81 assures operation of the air ducts to positively direct the air in the required direction under both heating and cooling conditions, and the system performs all its functions for either heating or cooling upon selection of either condition by movement of the manual switch 43 of the control 42.

Although this invention has been described in connection with particular air conditioning systems, other applications will readily be apparent to those skilled in the art. It is not, therefore, desired that the invention be limited to the specific arrangements illustrated and described and it is intended by the appended claim to cover all modifications within the spirit and scope of the invention.

What I claim as new and desire to secure by Letters Patent of the United States is:

55 An air conditioning system for heating and cooling the air in an enclosure comprising an air heating unit and an air cooling unit, each of said units including a heat transfer surface and a blower for circulating air thereover and for discharging the conditioned air from the unit, an outlet conduit, an outlet duct for each of said units for conducting air discharged from the respective units to said outlet conduit, automatic check dampers for preventing reverse flow of air in both said ducts, the check damper in one of said ducts being biased to a closed position by the force of air discharged from the other of said ducts, and means for selectively and alternatively operating said units to actuate their respective blowers and heat transfer units.
